ORSON D. BAYER, OF HARTFORD, CONNECTICUT, ASSIGNOR TO TRAVELERS INSURANCE COMPANY, OF HARTFORD, CONNECTICUT, A CORPORATION OF CONNECTICUT

SAFETY GUARD FOR PLUNGER MACHINES

Application filed June 30, 1928. Serial No. 289,561.

My invention relates to the class of devices that are employed to safeguard persons in the operation, more especially, of plunger machines, and an object of my invention, among others, is the provision of a guard that shall prevent injury to such persons by the unintentional placing of their hands in the path of movement of the reciprocating plunger of the machine.

10 One form of a safety guard embodying my invention, and in the construction and use of which the objects herein set out, as well as others, may be attained, is illustrated in the accompanying drawings, in which—

15 Figure 1 is a view in side elevation of a portion of a machine equipped with my improved safety guard.

Figure 2 is a view in front elevation of that portion of the machine shown in Figure 20 1 with my improved guard attached thereto.

Figure 3 is a view, scale enlarged, on a plane denoted by the dotted line 3—3 of Figure 1.

25 Figure 4 is a view in vertical section on a plane denoted by the dotted line 4—4 of Figure 3.

Figure 5 is a view similar to Figure 4, but illustrating the operation of my improved device.

30 In the accompanying drawings the numeral 6 indicates a portion of a frame of a plunger press in which a plunger 7 is mounted for reciprocating movement, said plunger having a head 8 at its lower end adapted to receive a die or other suitable device.

35 Any suitable means for reciprocating the plunger may be employed, this forming no part of my present invention, and for which reason a detailed illustration and description thereof are omitted herein.

40 The numeral 9 denotes the base of the press upon which a die support 10 is located to receive a die 11, all of which may be of any suitable and well known construction. The press herein illus-

45 trated and described is particularly employed for embossing operations upon stationery or similar material, although it will be understood that my invention may be well applied to any plunger press for performing any

50 operation.

The plunger presses of this type are commonly operated by means of a clutch, the members of which are thrown into or out of engagement in a manner that will be readily understood, and for the purpose of controlling the operation of the machine a clutch actuating handle 12 is suitably connected in any ordinary manner with the clutch mechanism for the purpose of operating it. In adapting my safety device to machines of this character I have so constructed the device that it will operate in connection with the handle 12 to operate said handle whenever the hands of an operative shall be located in a dangerous position while the plunger is descending.

55 My improved device comprises a guard 13 that is preferably of U-shape with an upward extension 14 on its front portion and with the branches thereof secured to the guard supporting levers 15 pivotally attached to the outer end of guard supporting arms 16. The arms 16, one for each of the levers 15, are secured at their inner ends to a rock shaft 17 pivotally mounted in a frame 18 secured to and rising from the base or bed 9 of the machine, and as illustrated in Figure 2 of the drawings. The levers 15 are connected, if desired, by a tie rod 19 to which one end of a spring 20 is attached, the other end of the spring being attached to the upper cross bar of the frame 18, and as shown in Figures 4 and 5 of the drawings.

60 A clutch tripping arm 21 is secured to one end of the shaft 17 and is connected by a clutch tripping rod 22 with a trip device supported on the frame 6.

65 In the structure herein shown this trip device comprises a supporting bar shown herein as conveniently formed of a front piece 23, a back piece 24 and spacers 25 located between and near the ends of the front and back pieces to provide a space therebetween for a purpose to be hereafter described. A bracket 26 is formed on the back of the back piece 24 within which bracket a trip shaft 27 is pivotally mounted. A trip arm 28 is secured to one end of the shaft 27 and a detent 29 is secured to the other end of the shaft. This detent 29 is located, in one posi-

55

tion, in the path of movement of a clutch actuating lever 30 pivotally supported at one end by the frame 6. A clutch actuating spring 31 is arranged to exert its force upon the lever 30 to move it to disconnect the clutch members and thereby stop operation of the machine. In the arrangement herein shown the spring is mounted upon a guide rod 32 pivotally attached at one end to the frame 6 and exerting its pressure at the opposite end against a thrust piece 33 pivotally attached to the lever 30.

In operation of the machine thus far described whenever the detent 29 is disengaged from the clutch actuating lever 30 the latter, under the force of the spring 31, operates the handle 12 to actuate the clutch mechanism, thereby disengaging the clutch members and permitting the machine to stop, it being understood that the machine is of a character which stops promptly upon the clutch members being disengaged.

To effect the operation of the trip mechanism hereinbefore described the parts are so arranged that movement of the guard supporting levers, under certain conditions, as when the hand of an operative is in a dangerous position, will rotate the rock shaft 17 to actuate the trip mechanism. In effecting this purpose an actuating finger 34 is attached preferably to each end of a rock shaft 35 pivotally supported in a bracket comprising bars 43 secured to opposite sides of the plunger head 8 and projecting beyond the back side thereof. The fingers 34 are adapted to engage lugs 36 projecting from the inner surfaces of the levers 15, a spring 37 on the shaft 35 acting on the latter to hold the fingers 34 normally in position to engage said lugs. A disengaging arm 38 is secured to the shaft 35 preferably at about the lengthwise center thereof, this arm acting in connection with a disengaging cam 39 secured to the cross bar of the frame 18 to disengage the fingers 34 from the lugs 36 at a time when danger of injury to a person's hand has passed. In the structure herein shown the arm 38 for convenience has a roller 40 traveling in contact with said cam.

In operation, if a person's hand 41 be placed in a dangerous position and liable to be struck by the plunger in its downward movement, and as shown in Figure 5 of the drawings, the guard 13 which surrounds the plunger will engage the hand and downward movement of this end of the guard will therefore be stopped, this downward movement having been caused to a slight extent by engagement of the fingers 34 with the lugs 36. When the downward movement of the outer end of the guard has thus been stopped the action of the fingers 34 on the lugs 36 will cause the ends of the levers opposite the guard 13 to be moved downwardly, thereby swinging the arms 16 to rock the shaft 17, which rock-

ing movement of the shaft 17 will, through the medium of the trip arm 21, actuate the trip rod 22 to operate the trip mechanism as hereinbefore described. This will effect stopping movement of the plunger before it has passed downwardly far enough to injure the hand that may be located thereunder.

The parts are so arranged that during the downward movement of the rearward ends of the levers 15, and just before the trip device is actuated to stop the machine, the fingers 34 will be disengaged from the lugs 36 and the spring 30 will thereupon return the guard to its upward or normal position, after danger to the hand has passed as hereinbefore described.

In normal operation of the machine the guard 13 will be moved downwardly at each downward movement of the plunger to a point sufficient to close the space between the plunger and the die 11 and enough to prevent a hand from being inserted into said space. Just as soon as this space is closed to this extent the fingers 34 are released from the lugs 36, in the manner hereinbefore described, and the guard 13 immediately moves to its upward position.

It will be understood that in this latter operation of the guard the arms 16 are held against a stop 42, as shown in Figure 4 of the drawings, and consequently, the ends of the levers 15 and arms 16 being in their raised positions, the guard 13 is permitted to travel to a lower position before the fingers 34 are disengaged from the lugs 36 than in the case where the rear ends of the levers 15 and arms 16 are in their lowered position and as shown in Figure 5 of the drawings.

The end of the shaft 17 adjacent to the arm 21 may be mounted in a supporting bar 44 secured to and projecting from the base 9 and as shown in Fig. 3 of the drawings.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim:

1. A safety guard mechanism including a handle for normal operation of the starting and stopping mechanism of a press, a member for moving the handle into a position to stop the press movably mounted on the frame of the press, means for moving said member against said handle to operate the latter, means for holding said member in its normal position of rest, a guard movably mounted in front of the space between the dies of said press, and an operative connection between said guard and said holding.

- means to release the latter to permit operation of said handle actuating member.
2. A safety guard mechanism including a handle for normal operation of the starting and stopping mechanism of a press, a lever for moving the handle into a position to stop the press pivotally mounted on the frame of the press, means for moving said lever against the handle to operate the latter, a 50 detent for holding said lever in its normal position of rest, a guard movably mounted in front of the space between the dies of said press, and an operative connection between said guard and said detent to release the latter to permit operation of said handle actuating member.
3. A safety guard mechanism including a handle for normal operation of the starting and stopping mechanism of a press, a lever for moving the handle into a position to stop the press pivotally mounted on the frame of the press, means for instantaneously moving said lever against said handle to operate the latter, a detent pivotally supported on said frame for holding said lever in its normal position of rest, a detent operating rod pivotally attached to said detent, a guard movably mounted in front of the space between the dies of said press, and an operative connection between said guard and said detent operating rod to operate said detent to release said lever to effect instantaneous operation of the handle actuating member.
4. A safety guard mechanism including a member for controlling the starting and stopping operations of a press, an operating member for said controlling member, a guard supporting lever mounted on the frame of the press for movement about two different pivots, a guard carried by said lever for reciprocating movement in front of the space between the dies of said press when the lever moves about one pivot, a connection between said operating member and said guard supporting lever for operation of the former to stop the operation of the press when the lever moves about the second pivot, means carried by the press plunger to move said guard supporting lever in one direction and means for moving said lever in the opposite direction.
5. A safety guard mechanism including a member for controlling the starting and stopping operations of a press, an operating member for said controlling member, a guard supporting lever, a guard carried by said lever for reciprocating movement in front of the space between the dies of said press, pivotally mounted arm on which said guard supporting lever is pivotally mounted, a connection between said pivotally mounted arm and said operating member for operation of the latter to stop the operation of the press, means carried by the press plunger to operate said arm in one direction, and means for moving said arm in the opposite direction.
6. A safety guard mechanism including a member for controlling the starting and stopping operations of a press, an operating member for said controlling member, a guard supporting lever, a guard carried by said lever for reciprocating movement in front of the space between the dies of said press, a pivotally mounted arm on which said guard supporting lever is pivotally mounted, a rock shaft to which said arm is secured, a connection between said rock shaft and said operating member for operation of the latter to stop the running of the press, means carried by said press plunger to operate said rock shaft in one direction, and means for operating said shaft in the opposite direction.
7. A safety guard mechanism including a member for controlling the starting and stopping operations of a press, an operating member for said controlling member, a guard supporting member movably mounted on the frame of the press, a guard carried by said supporting member for reciprocating movement in front of the space between the dies of said press, a connection between said guard supporting member and said operating member for operation of the latter to stop running of the press, a finger movably mounted for operation by the plunger of the press to engage said guard supporting member to move it in one direction, means for moving said guard supporting member in the opposite direction, and means for releasing said finger from said guard supporting member.
8. A safety guard mechanism including a member for controlling the starting and stopping operations of a press, an operating member for said controlling member, a guard supporting member movably mounted on the frame of the press, a guard carried by said supporting member for reciprocating movement in front of the space between the dies of said press, a connection between said guard supporting member and said operating member for operation of the latter to stop running of the press, a finger movably mounted for operation by the plunger of the press to engage said guard supporting member to move it in one direction, means for moving said guard supporting member in the opposite direction, and a cam positioned to operate said finger to disengage it from said guard supporting member.
9. A safety guard mechanism including a member for controlling the starting and stopping operations of a press, an operating member for said controlling member, a guard supporting member movably mounted on the frame of the press, a guard carried by said supporting member for reciprocating movement in front of the space between the dies of said press, a connection between said guard supporting member and said operating member for operation of the latter to stop the running of the press, a rock shaft carried by

- the press plunger, a finger secured to said rock shaft to engage said guard supporting member to move it in one direction, means for moving said guard supporting member in the opposite direction, and a cam positioned to rock said shaft to disengage said finger from said supporting member.
10. A safety guard mechanism including a member for controlling the starting and stopping operations of a press, an operating member for said controlling member, a guard supporting member movably mounted on the frame of the press, a guard carried by said supporting member for reciprocating movement in front of the space between the dies of said press, a connection between said guard supporting member and said operating member for operation of the latter to stop operation of said press, a rock shaft carried by the press plunger, a finger secured to said rock shaft to engage said guard supporting member to move it in one direction, means for moving said guard supporting member in the opposite direction, a disengaging arm secured to said rock shaft, and a cam positioned to engage said arm to rock said shaft to disengage said finger from said guard supporting member.
11. A safety guard mechanism including a member for controlling the starting and stopping operations of a press, an operating member for actuating said controlling member, a guard supporting member, a movably mounted support on which the guard supporting member is wholly and movably mounted, an operative connection between said movably mounted support and said operating member, and a guard carried by said guard supporting member for reciprocating movements in front of the space between the dies of the press.
12. A safety guard mechanism including a member for controlling the starting and stopping operations of a press, an operating member for actuating said controlling member, a guard supported for movement about two different pivots, means for normally moving the guard about one of said pivots, said guard being movable about the second pivot when an obstruction prevents its movement about the first pivot, and a connection between the guard and the operating member for actuating the latter when the guard is moved about its second pivot.
13. A safety guard mechanism including a member for controlling the starting and stopping operations of a press, an operating member for actuating said controlling member, a guard supported for movement about two different pivots, means operated by the action of the press for moving the guard, said guard being normally moved about one of its pivots and being moved about its second pivot when an obstruction prevents such normal movement, and a connection between

the guard and the operating member for actuating the latter when the guard is moved about its second pivot.

14. A safety guard mechanism including a member for controlling the starting and stopping operations of a press, an operating member for actuating said controlling member, a guard supported on a stationary portion of the press for movement about two different pivots, means operated by the action of the press for moving the guard, said guard being normally moved about one of its pivots and being moved about its second pivot when an obstruction prevents such normal movement, and a connection between the guard and the operating member for actuating the latter when the guard is moved about its second pivot.

15. A safety guard mechanism including a member for controlling the starting and stopping operations of a press, an operating member for actuating said controlling member, a movable guard support, a guard mounted on said support for normally moving with respect thereto, means for causing the guard support to move with the guard when an obstruction occurs in the path of movement of the guard, a connection between a movable portion of the press and the guard for providing motive power for the guard, and a connection between the guard and the operating member for actuating the latter when the guard and its support move together.
